APPARATUS FOR EFFECTING COUNTER-CURRENT CONTACT BETWEEN FLUIDS

Walter J. Podbielniak, Chicago, Ill.

Application June 25, 1936, Serial No. 87,222

18 Claims. (Cl. 261—83)

The present invention relates to improvements in apparatus for effecting counter-current contact between fluids and more particularly between liquids and vapors or gases, or between liquids of different densities that are more or less completely immiscible. It is particularly adapted for the distillation and fractionation of complex liquids, or for the fractional condensation or removal by absorption of constituents of vapor or gaseous mixtures. This application is a continuation-in-part of the invention disclosed in my prior co-pending application Serial No. 9,923 filed March 8, 1935, and is related to the invention described in my prior application Serial No. 5,059, filed February 5, 1935.

The invention will be fully understood from the following description, in which:

Fig. 1 is a longitudinal vertical sectional view through an apparatus suitable for carrying the invention into effect;

Fig. 2 is a transverse vertical sectional view on the line 2—2 of Fig. 1 looking in the direction of the arrows:

Fig. 3 is a transverse vertical sectional view on the line 3—3 of Fig. 1 looking in the direction of the arrows, parts being broken away for the purpose of illustration;

Fig. 4 is a fragmentary view on an enlarged scale with part removed, of a portion of the apparatus illustrated in Fig. 1;

Fig. 5 is a fragmentary view similar to Fig. 4 illustrating a modification adapted for use under different pressure conditions from those existing in Figs. 1 to 4; and

Fig. 6 is a view similar to Figs. 4 and 5 but illustrating a further modification adapted for use under still other pressure conditions.

In order that the invention may be fully understood it will be described in connection with a process of distillation, wherein vapors from a vaporizing receptacle containing mixed liquids are charged into the apparatus embodying my invention and passed counter-currently to condensate or reflux liquid travelling therethrough, for the purpose of effecting fractional condensation and separation of individual constituents of the vapors. Although reference will be made in the following description to such process it will be understood that the present invention is not limited thereto.

Referring more particularly to Figs. 1 to 4 inclusive of the drawings, numeral 10 indicates a stationary casing of generally cylindrical or drum-like form mounted upon a suitable stationary support 11. Casing 10 is provided at one end with a closure plate 12 having a central opening 13. An outwardly projecting conduit section 14 is secured in a fluid-tight manner in the central opening 13 of the closure plate 12. Conduit section 14 is provided at its end with a stuffing box

15 through which one extremity of a shaft 16 extends and is supported. The shaft 16 passes through the casing 10 and its other extremity extends outwardly therefrom. To the conduit section 14 there is provided a pipe or inlet conduit 17 by which vapor, from the distilling kettle, or other liquid fluid is supplied to the apparatus. The inlet conduit may be secured to conduit section 14 in any desired manner or may be formed integral therewith.

At its opposite end the casing 10 is closed by a plate 18 having a central opening 19 through which shaft 16 extends. An outwardly extending conduit section 20 and stuffing box 21 are secured in a fluid-tight manner in central opening 19. The shaft 16 extends through this conduit section and into stuffing box 21 in which it is supported. The conduit section 20 communicates with the exit pipe 22 for treated vapor or gas, and through which reflux liquid or other heavy liquid may be supplied as required. The exit pipe 22 may be secured in any desirable manner to the conduit section 20 or may be formed integral therewith.

Within the casing 10 and spaced therefrom, a cylindrical rotor designated as a whole by the numeral 23, is mounted for rotation upon the shaft 16. The rotor 23 may suitably comprise end plates 24 and 25 and an intermediate spirally wound sheet 26 surrounded by a cylindrical shell 28. The sheet 26 is coiled as best illustrated in Fig. 2, so that one end, conveniently referred to as the inner end, is spaced only a short radial distance from the shaft 16 and its outer end is near the casing 28. The turns or coils of spiral sheet 26 are spaced radially so as to form a spiral passageway 27 of increasing radius. The outer end of sheet 26 forms with the shell 28 an inlet 29 to this passageway.

The end plate or head 24 of rotor 23 may be secured in a fluid-tight manner to one edge of spiral sheet 26 and shell 28 as by a weld or solder. The end plate 24 is provided with a central opening through which shaft 16 extends and a fluid-tight keying means as at 31 is provided to establish mutual rotation between the shaft and end plate. The end plate or head 25, however, is illustrated as having a spiral groove therein which receives the other edge of spiral sheet 26. The head 25 is bolted to a flange on shell 28 as shown at 33 so that head 25 is forced against the edge of sheet 26 to form a fluid-tight joint therewith. The fluid-tight joints between members 24, 25 and 28 and between members 16 and 24 prevent fluid from by-passing passage 27 and ensure that the fluids supplied to opposite ends of passage 27 traverse such passage in opposite directions and so cause the maximum action on each other.

As appears best in Fig. 2, the inner end of the 60

sheet 26 is spaced from the shaft 16 to provide a space or chamber 32 from which fluid may enter the passage 27 or through which it may discharge therefrom. As stated above, the outer end 5 of sheet 26 is spaced from the shell 28 to provide a space or chamber 29. Fluid may be discharged from the passage 27 into space 29 or, as stated above, space 29 may serve as an inlet for fluid into this passage. Provision for a flow of fluid 10 to and from space 29 is obtained by openings 33, 33, in the plate 24, which are arranged in a ring close to shell 28. The openings 33 connect the space 29 with a device on the outside of the plate 24 which serves as a liquid sealing and a liquid 15 discharge device, the construction of which is as follows:

The end plate 24, which is secured to and rotates with the shaft 16, is of generally circular form and extends somewhat beyond the rotor 20 casing 28, the projecting annular portion being indicated at 34. An annular member 35 of generally L shape cross-section is secured as by a fluid-tight connection to the end plate 24. Member 35 rotates with the end plate 24 and forms therewith an annular chamber for a body of 25 liquid. To the inner side of the end plate 12 of casing 10 there may be secured a conduit section 36 which provides an opening that communicates from the opening 13 in end plate 12 30 with the opening in conduit section 14, and forms a continuation of the latter. A stationary flat plate 37 is secured to the free end of conduit section 36 forming a wide annulus which is parallel to and spaced from plate 24. The outer edge of 35 annulus 37 extends into the body of liquid in the annular chamber formed by the projecting portion 34 of the rotor end plate 24 and the annular member 35. On the plate 37 there is mounted a plate 38 of smaller diameter, spaced somewhat 40 from the plate 37 and also from plate 24. This member is provided with a central opening 39 through which the shaft 16 passes. Opening 39, however, is larger than the shaft to permit a desired flow of vapors or like fluids from conduit sections 14 and 36 into the space between the 45 rotary plate 24 and the stationary plate 38. The outer edge of the plate 38 is secured to the plate 37 by a ring 40 (Fig. 4) having in it a large number of openings 41 (Figs. 1 and 4). Fixed to one 50 face of the plate 38, and extending into the space 52 between such plate and the plate 37 are flow-impeding ridges or corrugations 42 (Fig. 3), the purpose of which will presently appear. As will be hereinafter pointed out, the assemblage of the 55 stationary plates 37 and 38, in the manner described, within the annular chamber formed by the end plate 24 of the rotor and the annular member 35, provides both a sealing means and a liquid collecting or discharge means.

60 The end plate 25 at the opposite end of the rotor 24, is provided at its center with an opening 43, which communicates with the space 32 in the interior of rotor 23. An outwardly projecting cylindrical conduit section 44, secured 65 in any desirable manner to the end plate 25 at the opening 43, is provided with a spider 45, by which the end plate 25 may be mounted for rotation on the shaft 16. The spider 45 and the connection 46 thus provide the means for establishing mutual rotation of the rotor 23 and the shaft 16. The conduit section 44 leading from the central portion of the rotor communicates with a stationary conduit section 46, extending inwardly 70 from the end plate 18 of the casing 10 75

at the opening 19. Conduit section 46 in turn, communicates with the conduit section 20.

The construction of my apparatus is such that condensate or reflux is formed in the passage-ways described and this condensate or reflux is 5 made use of in a seal to prevent the escape of vapors passing from the rotor 23 to the exit pipe 22.

The seal is formed as shown in Fig. 1 and may comprise an outwardly projecting flange member 10 47 formed integral with the end of conduit section 46. Member 47 is in effect a wide annular plate to which an L-shaped circular member 48 may be secured in a fluid-tight manner. Members 47 and 48 cooperate to form an annular 15 chamber into which the liquid reflux is propelled by centrifugal force. The inner walls of the annular chamber may be provided with ribs or corrugations to assist the movement of the fluid in the seal. An upstanding flange member 49 is 20 formed integral with conduit section 46 and is arranged substantially centrally of the annular chamber. The outer end of member 49 is adapted to extend into the body of liquid and thus prevent the escape of vapors passing through the 25 seal.

The apparatus illustrated in Figs. 1 and 2 is assumed to be connected, by way of example, to a still by means of conduit 17 and its operation under such conditions is as follows:

Vapors, from a distilling kettle or like device, to be fractionated, enter the conduit sections 14 and 36 from the pipe 17. They pass through the opening 39 in the annular member 38 which forms, as heretofore stated, a part of the liquid 35 seal and discharge device, the operation of which will be hereinafter described. Vapors then travel outwardly and enter the openings 33 of the end plate 24 of rotor 23. The rotor is rotated at a speed suitable to develop the centrifugal force 40 necessary for the operation, by a motor and belt (not shown), and the pulley 16' on one end of the shaft 16. The vapors are supplied under pressure sufficient to cause them to travel inwardly 45 through the rotor being forced by such pressure to traverse the passage 27 inwardly from the space 29 and to contact, in such passage, with reflux liquid or other liquid passing counter-currently thereto. Preferably, plate 24 has impeller 50 or booster blades 58 affixed to its outer face and which are positioned between itself and plate 38. Vanes 59 serve to assist the flow of vapors or other light fluid through the openings 33. When the vapors reach the space 32 at the center of the 55 rotor, they pass out through the central opening 43 in the rotor head plate 25, thence through the conduit sections 44, 46 and 20 to the exit pipe 22. As stated above, the liquid seal between conduit sections 44 and 46 prevents the escape of vapors from the rotor 23.

60 Reflux liquid for cooling purposes may be supplied to the pipe 22 in the required amounts and enters the rotor through the conduit sections 28 and 46, passing into the projecting portion 44 of the end plate 25 of rotor 23, and thus into the 65 space 32 surrounding the shaft 16. The reflux or like liquid as well as the condensate formed in passage 27, builds up a film or layer on the face of the sheet 26 and travels under the action of centrifugal force resulting from the rotation 70 of the rotor through the passage 27 into the space 29 from which it discharges through the openings 33.

In its travel through the rotor, the liquid moves counter-currently to the flow of vapor passing 75

therethrough and intimate contact between the liquid film and the vapor throughout the entire length of passage 27 is assured.

The liquid discharged through the openings 33 enters the rotating chamber formed by the projecting portion 34 of the end plate 24 of the rotor and the annular member 35. The liquid accumulating in the bottom of this chamber, rotates therewith and is formed into an annular liquid body (as shown at 51) by the centrifugal force set up during rotation. To assist the movement of the body of liquid, the inner walls of the annular chamber may be provided with ribs or corrugations. The outer edge of stationary plate 37 projects into the annular body of liquid and thereby forms a liquid seal adapted to prevent vapors leaving the rotor 23 at the end from which liquid is withdrawn. As liquid continues to flow into the annular chamber, the chamber becomes filled, and thereupon the liquid enters the openings 41 and the stationary space 52 between the plates 37 and 38. Liquid entering space 53 through openings 41 has considerable velocity of rotation which, unless checked, retards the discharge of liquid from such space. I accordingly provide plate 38 with impeding ridges or corrugations 42 (Fig. 3), lying in space 52, to check the rotation of liquid therein. From space 52, liquid flows out through the conduit sections 36 and 14 to the pipe 17 by which it may be returned to the kettle or receptacle from which vapors are supplied to the system.

The space within casing 10 and surrounding the rotor 23 may be maintained under atmospheric pressure or under any suitable pressure other than atmospheric. In order to prevent or avoid the necessity of constructing the rotor 23 to withstand undue pressures, it is desirable that the interior of the casing 10 be maintained under a pressure approximately the same as that prevailing within the interior of the rotor and, in the specific case described, within the distillation system. For this purpose, a pressure regulator and controller 53 is shown, this being of well known character and supplied with a suitable inert gas such as carbon dioxide or with air or other gas if desired, through the pipe 54. The gas thus supplied is conducted to the interior of the casing through the pipe 55. The pressure within the casing is controlled by the pressure regulator 53 to maintain a fixed relationship to that prevailing within the exit conduit 22. The pressure in exit conduit 22 is communicated to the pressure regulator 53 through the pipe 56.

As exit conduit 22 is in communication with the interior of the rotor 23, pressure regulator 53 maintains a constant relationship between the pressure at any given point in such rotor, for example space 57 in the liquid discharge and sealing device, and that in the space surrounding it. The pressure of the medium surrounding the rotor 23 will be seen to exert itself against the surface of the body liquid 51 at points outside the stationary plate 37, while the surface of the body of liquid 51 within plate 37 is subjected to the pressure of the medium in space 57 between the outer portion of the plate 38 and the outer face of plate 24. Such pressure is substantially that of the vapors or lighter fluid in the space 29.

The liquid in body 51 is of course, free to flow around the outer edge of plate 37 and a difference in the pressures on the surface of body 51 on opposite sides of the plate causes such a flow to occur until the liquid on one side is sufficiently

increase in centrifugal force in the deeper portion of body 51 off-setting difference in static pressures at its surface. Consequently the surface of the liquid body 51 outside the plate 37 may not be the same distance from shaft 16 as the surface of such body inside plate 37. The radial dimension of the plate 38 and the consequent position of the holes 41 through which the liquid discharges from body 51 may advantageously be different in installations having different pressure conditions, to adapt the liquid discharge means to the pressure conditions in order to keep the seal dimension and its liquid content at a minimum. Obviously also for any given construction of the plate 38, the pressure differential between the space surrounding the rotor and the space 57 between the plates 38 and 24 should be maintained reasonably constant to suit the construction of the plate 38. Such result is obtained by the action of the pressure regulator 53.

However, different pressure relations, or a variation in the pressure differential, may often be desired in different installations. Figs. 4, 5 and 6 illustrate three different relations between the pressure external to the rotor and that within it in the space 29. These figures show the variations in design of the plate 38 and the discharge chamber 52 between plates 37 and 38 advantageous for such differences in pressure conditions. In Fig. 4, I have illustrated a liquid seal and discharge chamber designed to operate in an apparatus having zero pressure differential between the space surrounding the rotor 23 and that in the spaces 29 and 57. It will be seen that in Fig. 4, the surface of liquid body 51 has the same distance from the shaft on both sides of plate 37.

In the modification shown in Fig. 5, it is assumed that the pressure surrounding the rotor 23 is greater than that in the spaces 29 and 57. The surface of the liquid of body 60 on the outside of plate 37 is therefore farther from the shaft than the surface of such body inside the plate. In the modification shown in Fig. 6, it is assumed that the pressure surrounding the rotor 23 is less than that within the rotor in the space 61. The surface 45 of the liquid body 62 on the outside of plate 37 is therefore closer to the shaft than the surface of such body inside of the plate. In each of Figs. 4, 5 and 6, the discharge means is designed so that the openings 41 shall lie at the surface of the liquid on the inside of plate 37 so that additional fluid discharged through opening 33 will pass out through the discharge chamber. This condition requires that in the arrangement of Fig. 5, the plate 63 have a less radius than plate 38 in Fig. 4, while the plate 64 of Fig. 6 shall have a greater radius than that of plate 38.

It is evident that a pressure differential between spaces 57, 59 or 61 and the space in casing 10 outside rotor 23, if too great, will cause either a loss of liquid into casing 10 or a flow of relatively cold foreign gas into the interior of the rotor. The pressure regulator 53 or equivalent means for maintaining constant pressure relations in the apparatus, therefore not only affects the construction of rotor 33, but also is important in ensuring satisfactory operation of the liquid sealing means supra whenever material pressure variations occur between the inlet and outlet of the rotor. While valved pipe 65 connecting inlet conduit 17 with the interior of housing 10 may be used to maintain a pressure differential between the interior and exterior of the rotor, it cannot be used to equalize pressures on 75

the liquid in the liquid sealing means when fan blades 58, or their equivalent, are employed.

The layer or depth of liquid formed on the sheet 28 has a thickness depending upon the characteristics of the liquid and the centrifugal force developed in the operation. While this centrifugal force may be approximately equal to the force exerted by gravity or even less, it is preferred that it be substantially in excess of the force of gravity and preferably at least twice. In general, I have found it advisable to employ conditions of operations, rates of rotation and the like so that the centrifugal force effected in the operation is equivalent to five or more times the force of gravity. A speed of rotation at 600 to 2000° R. P. M. or higher has been found suitable. At this speed a clearance between the relatively moving parts of the seals heretofore described of approximately $\frac{1}{8}$ " has been found satisfactory when utilizing a seal diameter of approximately eight inches.

The traverse of the liquid within spaces 32 and 29 in the rotor 23 is in general parallel to the axis of rotation while, in the passage 27, it is 25 in general transverse to such axis.

The apparatus shown in the drawings is designed for operation with the shaft in the horizontal position but it may be arranged so that the shaft is mounted vertical or at an intermediate angle, since the main force compelling the movement of the liquid through the system is centrifugal and static pressure is employed to force the vapors through the system.

While the invention has been described hereinbefore in connection with distillation operations, it is readily apparent that it is also applicable to other operations in which counter-current contact between vapors and liquids are desired. For example, in absorption processes for 40 removing constituents from natural gas or other gases, by absorption in oil or other liquids or in processes wherein constituents of gases are removed by chemical action, as in the removal of hydrogen sulfide from gases by contact with alkali 45 solutions, such as solutions of soda ash, triethanolamine and the like. The invention may also be employed in processes where counter-current contact between liquids of different densities which are more or less immiscible with one another is desired. For example, in solvent processes for removing constituents of lubricating 50 oils and the like or the chemical refining of hydrocarbon oils with sulfuric acid, alkalis or the like. In these instances suitable means being 55 provided for the introduction of the heavier and lighter fluids into the rotor.

Although the present invention has been described in connection with details of specific apparatus and processes for carrying the same into effect, it is to be understood that such details are not to be recorded as limitations upon the scope of the invention, except in so far as included in the accompanying claims which form a part of this specification. Thus, the seals heretofore 60 described may be inverted; that is, the annular chamber may be made stationary and the member extending into the annular body of liquid may rotate with the rotation of the rotor. In this instance the rotating member may be provided 65 with ribs or corrugations to assist the flow of the annular body of liquid in the stationary seal chamber.

I claim:

1. In an apparatus for the counter-current contact of fluids in a zone of centrifugal force,

a rotor having a spiral passageway, means for supplying a relatively heavier fluid within said rotor so that it flows outwardly through said passageway upon rotation, means for supplying a relatively lighter fluid to the outer end of said passageway under sufficient pressure so that it flows inwardly therethrough, means for discharging said lighter fluid from said rotor, means for discharging said heavier fluid from the rotor and a casing surrounding said rotor, said means 10 for discharging said heavier fluid comprising a liquid seal means having a body of liquid therein, means forming a passageway for the flow of liquid from said body and having an extension into said body which separates the surfaces thereof so that one surface is in communication with the interior of the rotor and the other is in communication with the exterior of the rotor.

2. In an apparatus for the counter-current contact of fluids in a zone of centrifugal force, 20 a rotor having a spiral passageway, means for supplying a relatively heavier fluid within said rotor so that it flows outwardly through said passageway upon rotation, means for supplying a relatively lighter fluid to the outer end of said passageway under sufficient pressure so that it flows inwardly therethrough, means for discharging said lighter fluid from said rotor, means for discharging said heavier fluid from the rotor and a casing surrounding said rotor, said means 25 for discharging said heavier fluid comprising a liquid seal means having a body of liquid therein, means forming a passageway for the flow of liquid from said body and having an extension into said body which separates the surfaces thereof so that one surface is in communication with the interior of the rotor and the other is in communication with the exterior of the rotor, 30 said passageway for the flow of liquid from said body being in communication with the surface of said body that communicates with the interior of the rotor.

3. In an apparatus for the counter-current contact of fluids in a zone of centrifugal force, 40 a rotor having a spiral passageway, means for supplying a relatively heavier fluid within said rotor so that it flows outwardly through said passageway upon rotation, means for supplying a relatively lighter fluid to the outer end of said passageway under sufficient pressure so that it flows inwardly therethrough, means for discharging said lighter fluid from said rotor, means for discharging said heavier fluid from the rotor and a casing surrounding said rotor, said means 45 for discharging said heavier fluid comprising a liquid seal means having a body of liquid therein, means forming a passageway for the flow of liquid from said body and having an extension into said body which separates the surfaces thereof so that one surface is subjected to the pressure in the rotor and the other is subjected to the pressure outside the rotor whereby the surface subjected to the least pressure is more proximate to the axis of the rotor than the other surface.

4. In an apparatus for the counter-current contact of fluids in a zone of centrifugal force, a rotor having a spiral passageway, means for supplying a relatively heavier fluid within said rotor so that it flows outwardly through said passageway upon rotation, means for supplying a relatively lighter fluid to the outer end of said passageway under sufficient pressure so that it flows inwardly therethrough, means for discharging said lighter fluid from said rotor, means for discharging said heavier fluid from the rotor and

- a casing surrounding said rotor, said means for discharging said heavier fluid comprising a liquid seal means having a body of liquid therein, means forming a passageway for the flow of liquid from said body and having an extension into said body which separates the surfaces thereof so that one surface is subjected to the pressure in the rotor and the other is subjected to the pressure outside the rotor, the surface subjected to the pressure in the rotor being more proximate to the axis of the rotor than the other, said passageway for the flow of liquid from said body being in communication with the surface of said body more proximate to the axis of the rotor.
5. In an apparatus for the counter-current contact of fluids in a zone of centrifugal force, a rotor having a spiral passageway, means for supplying a relatively heavier fluid within said rotor so that it flows outwardly through said passageway upon rotation, means for supplying a relatively lighter fluid to the outer end of said passageway under sufficient pressure so that it flows inwardly therethrough, means for discharging said lighter fluid from said rotor, means for discharging said heavier fluid from the rotor and a casing surrounding said rotor, said means for discharging said heavier fluid comprising a liquid seal means having a body of liquid therein, means forming a passageway for the flow of liquid from said body and having an extension into said body which separates the surfaces thereof so that one surface is subjected to the pressure in the rotor and the other is subjected to the pressure outside the rotor, the surface subjected to the pressure in the rotor being more distant from the axis of the rotor than the other, said passageway for the flow of liquid from said body being in communication with the surface of said body more distant from the axis of the rotor.
6. The combination in an apparatus for the contact of fluids in a zone of centrifugal force of a rotor having a passage whose ends are spaced radially of the axis of rotation and adapted to create a centrifugal action, means for supplying a relatively heavier fluid within said rotor so that it flows outwardly through said passage upon rotation, means for supplying relatively lighter fluid to the outer end of said passage and at sufficient pressure to force it inwardly therethrough, means for discharging said relatively heavier and relatively lighter fluids from said rotor, the means for discharging said relatively heavier fluid being included in a seal, a stationary casing surrounding said rotor and means for maintaining the pressure in said casing outside said rotor at a constant relation to the pressure at a given point within the rotor.
7. The combination in an apparatus for the contact of fluids in a zone of centrifugal force of a rotor having a passage adapted to create a centrifugal action, means for supplying a relatively heavier fluid within said rotor so that it flows outwardly through said passage upon rotation, means for supplying a relatively lighter fluid to the outer end of said passage under sufficient pressure so that it flows inwardly therethrough, means included in a seal for discharging said relatively heavier fluid from said rotor, means for discharging said relatively lighter fluid therefrom, a stationary casing surrounding said rotor and means for maintaining a fluid in said casing surrounding said rotor at a pressure approximately the same as that at the point of discharge of said heavier fluid from the rotor.
8. The combination in an apparatus for the contact of fluids in a zone of centrifugal force of a rotor having a passage whose ends are spaced radially of the axis of rotation, means for supplying a relatively heavier fluid within said rotor so that it flows outwardly through said passage upon rotation, means for supplying a relatively lighter fluid to the outer end of said passage under sufficient pressure to cause it to flow inwardly therethrough, means for discharging said relatively heavier fluid from said rotor, means included in a seal for discharging relatively lighter fluid from said rotor, a casing surrounding said rotor and spaced therefrom and means for maintaining a pressure in said casing outside said rotor greater than that at the point of discharge of said heavier fluid from the rotor.
9. The combination in an apparatus for the contact of fluids in a zone of centrifugal force of a rotor having a passage whose ends are spaced in the direction radially of the axis of rotation, means for supplying a relatively heavier fluid within said rotor so that it flows outwardly through said passage upon rotation, means for supplying a relatively lighter fluid to the outer end of said passage under a force sufficient to cause it to flow inwardly therethrough, means included in a seal for discharging said relatively heavier fluid from said rotor, means for discharging said relatively lighter fluid from said rotor, a casing surrounding said rotor and means for maintaining in said casing outside said rotor a fluid pressure less than that at the point of discharge of said heavier fluid from the rotor.
10. The combination in an apparatus for the contact of fluids in a zone of centrifugal force of a rotor having a passage whose ends are spaced in the direction radially of the axis of rotation and adapted to create a centrifugal action, means for supplying a relatively heavier fluid within said rotor so that it flows outwardly through said passage upon rotation, means for supplying a relatively lighter fluid to the outer end of said passage under pressure sufficient to force it inwardly therethrough, a casing surrounding said rotor and spaced therefrom, means for discharging said relatively lighter fluid from said rotor, means for maintaining the pressure in the space between said rotor and casing in fixed relation to that at a point within said rotor, and means for discharging said heavier fluid from said rotor comprising a liquid seal means having a body of liquid therein, a stationary chamber extending to the surface of said liquid and provided with one or more openings through which liquid from said seal may enter such chamber, and means within said stationary chamber for checking the rotary motion of liquid entering the chamber from said body.
11. The combination in an apparatus for the contact of fluids moving in continuous uninterrupted streams in a zone of centrifugal force, of a drum type rotor having a passage whose ends are spaced in the direction radially of the axis of rotation and adapted to create a centrifugal action, means for supplying a relatively heavier fluid within said rotor so that it flows outwardly through said passage upon rotation, means for supplying a relatively lighter fluid to the outer end of said passage under pressure sufficient to force it inwardly therethrough, a shaft for said rotor, a stationary casing surrounding said rotor and spaced therefrom, said casing having an opening through which said shaft extends, said casing having a second opening adjacent to and coaxial with the axial opening in said rotor and

through which said shaft extends, and liquid seal means surrounding said shaft intermediate said openings comprising an annular member supported by said rotor to revolve therewith and adapted upon rotation to contain a body of sealing fluid, and a plate fixed to said outer casing and adapted to extend into the ring of fluid within said member to form a seal.

12. The combination in an apparatus for the contact of fluids in a zone of centrifugal force of a rotor having a continuous uninterrupted passage whose ends are spaced in the direction radially of the axis of rotation and adapted to create a centrifugal action, means for supplying a relatively heavier fluid within said rotor so that it flows outwardly through said passage upon rotation, means for supplying a relatively lighter fluid to the outer end of said passage under pressure sufficient to force it inwardly therethrough, a casing surrounding said rotor and spaced therefrom, means for discharging said relatively lighter fluid from said rotor, means for maintaining the pressure in the space between said rotor and casing in fixed relation to that at a point within said rotor, and means for discharging said heavier fluid from said rotor comprising a liquid sealing means having a body of liquid therein, a stationary chamber extending to the surface of said liquid and provided with one or more openings through which liquid from said seal may enter such chamber.

13. The combination in an apparatus for contacting a liquid and a relatively lighter fluid in a zone of centrifugal force of a rotor having a passage in which such contact occurs, means for feeding liquid to the interior of said rotor so that it passes outwardly through said passage, a liquid sealing and discharge means having an annular chamber arranged to rotate with said rotor, and to receive liquid which has passed outwardly through said passage so as to form an annular body, a stationary plate whose outer edge projects beneath the surface of said body of liquid, means to withdraw liquid from between said rotor and stationary plate, and means to maintain a constant relationship between the pressures on the surfaces of said body on opposite sides of said plate.

14. In a fluid counter-current apparatus, a rotor having a liquid sealing and discharge device comprising in combination a rotating plate, means forming an annular chamber fixed to said plate and adapted to rotate therewith, means through which liquid is fed to said chamber to build up an annular liquid body therein during rotation, a fixed plate parallel to said plate and spaced therefrom, said fixed plate having its edge normally extending beneath the surface of said body, means for withdrawing liquid from the surface of said body, and means for maintaining a constant relationship between pressures on the parts of the surface of said body on opposite sides of said stationary plate.

15. The combination in an apparatus for counter-currently contacting fluids in a zone of centrifugal force of a rotor within which fluids are contacted and having liquid sealing and discharge means associated therewith comprising means forming an annular chamber mounted to rotate with said rotor, means for feeding liquid from said rotor to said chamber to build up an annular liquid body therein, a fixed plate normally extending beneath the surface of said liquid body, means to withdraw liquid from said

body at points between said plate and rotor, a fixed casing enclosing said rotor, said sealing and discharge means being so arranged that the pressure within said casing and outside said rotor exerts itself on one part of the surface of said liquid body and the pressure at a point within said rotor exerts itself on another part of the surface of said body, and means to regulate the pressure within said casing outside said rotor to maintain a constant relationship to the pressure within the rotor.

16. In an apparatus for the counter-current contact of fluids in a zone of centrifugal force, a rotor having a spiral passageway, means for supplying a relatively heavier fluid within said rotor so that it flows outwardly through said passageway upon rotation, means for supplying a relatively lighter fluid to the outer end of said passageway under sufficient pressure so that it flows inwardly therethrough, means for discharging said lighter fluid from said rotor, means for discharging said heavier fluid from the rotor, a casing surrounding said rotor, said means for discharging said heavier fluid comprising a liquid seal means having a body of liquid therein, means forming a passageway for the flow of liquid from said body and having an extension into said body which separates the surfaces thereof so that one surface is in communication with the interior of the rotor and the other is in communication with the exterior of the rotor, and means to regulate the pressure within said casing outside said rotor to maintain a constant relationship to the pressure within the rotor.

17. In apparatus for effecting counter-current contact between fluids, a rotor and means for effecting rotation thereof, means for supplying a liquid within the rotor to pass outwardly therethrough and means for supplying a lighter fluid at an outer point to pass inwardly therethrough, means for rotating said rotor to cause outward movement of the heavier fluid, an annular chamber at one end of said rotor and rotatable therewith, said chamber having openings communicating with the interior of the rotor to receive heavier fluids discharged therefrom, and a stationary collector chamber extending into said annular chamber, said collector chamber being formed of spaced circular plates having openings therebetween through which liquid collected in said annular chamber may enter the collector chamber formed between said plates.

18. In apparatus for effecting counter-current contact between fluids, a rotor and means for effecting rotation thereof, means for supplying a liquid within the rotor to pass outwardly therethrough and means for supplying a lighter fluid at an outer point to pass inwardly therethrough, means for rotating said rotor to cause outward movement of the heavier fluid, an annular chamber at one end of said rotor and rotatable therewith, said chamber having openings communicating with the interior of the rotor to receive heavier fluids discharged therefrom, and a stationary collector chamber extending into said annular chamber, said collector chamber being formed of spaced circular plates having openings therebetween through which liquid collected in said annular chamber may enter the collector chamber formed between said plates, one of said plates extending beyond the other and into the fluid in said annular chamber, thereby forming a seal.

CERTIFICATE OF CORRECTION.

Patent No. 2,109,375.

February 22, 1938.

WALTER J. PODBIELNIAK.

It is hereby certified that error appears in the printed specification of the above numbered patent requiring correction as follows: Page 5, second column, line 11, claim 8, strike out the words "included in a seal" and insert the same after "means", line 9, same claim; page 6, first column, line 49, claim 14, for "fluid" read fluid-fluid; and that the said Letters Patent should be read with these corrections therein that the same may conform to the record of the case in the Patent Office.

Signed and sealed this 12th day of April, A. D. 1938.

Henry Van Arsdale,

Acting Commissioner of Patents.
